Robert N. Tate

UNITED STATES PATENT OFFICE.

ROBERT N. TATE, OF NEW LONDON, CONNECTICUT.

MAST-SCRAPER.

Specification of Letters Patent No. 26,535, dated December 20, 1859.

To all whom it may concern:

Be it known that I, ROBERT N. TATE, of New London, in the county of New London and State of Connecticut, have invented a new and useful Implement or Device for Scraping the Masts of Vessels; and I do hereby declare that the following is a full, clear, and exact description of the same, reference being had to the annexed drawings, 10 making a part of this specification, in which—

Figure 1, is a side view of my invention. Fig. 2, an end view of ditto.

Similar letters of reference indicate corresponding parts in the two figures.

The object of this invention is to obtain an implement that will facilitate the scraping of the masts of vessels without injuring or cutting the same during the operation. This 20 work is at present performed with ordinary knives and the operation is not only slow and tedious, but the masts are liable to be cut or scored in consequence of the comparatively straight edges of the knives acting against the convex surfaces of the masts.

The within described invention consists in having a steel plate provided with a concave edge or edges corresponding with the convexity of the mast or masts to be scraped, 30 said plate being attached to a suitable tang or handle so that the plate may be drawn down against the mast and a comparatively long concentric scraping surface made to act upon it.

35 To enable those skilled in the art to fully understand and construct my invention I will proceed to describe it.

A, represents a steel plate which is of trilateral form and is secured to a tang B, the 40 latter having a shoulder *a*, on it against which the plate bears, and is pressed snugly against it by a nut *b*, the tang passing through the center of the plate. The tang B, is secured in a wooden handle C. The 45 three edges or sides *c*, *d*, *e*, of the plate A, are concave forming portions of circles of different diameter, for instance the side *c*, forms a portion of a circle of 12 inches diameter, the circle corresponding with side *d*, 50 is 18 inches diameter and the circle corre-

sponding with side *e*, 24 inches diameter, see Fig. 3, in which the smallest circle is shown in red.

Each side of the plate A, is brought to an edge by a basil on the outer side of the plate. From this description it will be seen that if a mast 12 inches in diameter is to be scraped, the side *c*, of the plate would be used and at each stroke of the tool a portion of the surface of the mast corresponding in width 55 to the length of the side *c*, will be scraped. If the mast to be scraped is 18 inches in diameter, the side *d*, is used and if 24 inches in diameter the side *e*, is operated with. The advantage of this tool over an ordinary 60 knife which can act upon a small surface only of the mast at each stroke will be readily seen.

The plate A, may have only one concave edge or side, or it may be formed with 70 three, four, or even more sides. In the manufacture of them they will probably be furnished with a different number of edges, from one upward, the implements varying 75 in price according to the number of edges or sides they may have.

I am aware that trilateral scrapers are now in common use for scraping the decks and sides of vessels; but these scrapers have straight edges and are employed only for 80 scraping plane surfaces or those approximating thereto, and therefore could not be employed for scraping masts with any better results than the knives now employed.

I do not claim the employment or use of 85 a trilateral or polygonal plate as a scraper irrespective of the concave sides or edges herein described; but,

I do claim as new and desire to secure by Letters Patent,

An implement or tool composed of a steel plate A, provided with one or more concave edges, and attached to a suitable tang or handle, to form a new and useful article of manufacture for the purpose herein set 90 forth.

ROBERT N. TATE.
